(57) **CLAIM**

The ornamental design for a computing device with illumination, as shown and described.

DESCRIPTION

FIG. 1 is a front perspective view of a computing device showing my new design in an unilluminated state;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is an enlarged view of the encircled portion in FIG. 2;

FIG. 9 is a front perspective view of a computing device of FIGS. 1-8 showing an illuminated state;

FIG. 10 is a front view thereof;

FIG. 11 is a rear view thereof;

FIG. 12 is a left side view thereof;

FIG. 13 is a right side view thereof;

FIG. 14 is a top view thereof;

FIG. 15 is a bottom view thereof; and,

FIG. 16 is an enlarged view of the encircled portion in FIG. 10.

The even-length broken lines depicting the remainder of the computing device shows features that form no part of the claimed design. The uneven-length broken lines showing of the encircled portions form no part of the claimed design. The radiating lines emanating from FIGS. 9, 10, and 16 represent illumination. The difference in shading indicates a contrast of appearance and does not depict any particular color, texture, or material.
